UNITED STATES PATENT OFFICE.

CHARLES HENRY LIKEWISE, OF NEW YORK, N. Y.

STEP-LADDER.

SPECIFICATION forming part of Letters Patent No. 621,260, dated March 14, 1899.

Application filed May 2, 1898. Serial No. 679,432. (No model.)

To all whom it may concern:

Be it known that I, CHARLES HENRY LIKEWISE, a citizen of the United States, residing at New York, (Brooklyn,) in the county of Kings and State of New York, have invented 5 certain new and useful Improvements in Step-Ladders; and I do hereby declare the following to be a full, clear, and exact description of the invention, such as will enable others 10 skilled in the art to which it appertains to make and use the same.

My invention relates to step-ladders, the object, among others, being to provide a ladder which while possessing all the advantages 15 of the most modern step-ladders shall in addition to these be capable of being folded into a very small compass for convenience in shipping, packing, and storing as well as for moving from place to place in a building and for 20 carrying in the hand from one building to another or from one locality to another where it is found necessary to use street-cars or other means of conveyance.

The advantages, construction, and operation 25 of my invention will be fully pointed out in the appended specification and illustrated in the accompanying drawings, which form a part of this application, in which—

Figure 1 is a perspective view of my ladder 30 complete and in operative position. Fig. 2 is a perspective view showing it partly folded. Fig. 3 is a detail plan view of one of the joints used in the legs of my ladder. Fig. 4 is a detail 35 illustrating the method employed for attaching and securing the stay-bolts in their operative positions. Figs. 5 and 6 are views showing ladder compactly folded.

For convenience of reference the same numerals will be used to designate the same parts 40 throughout the several views.

The numerals 1 and 2 designate the front legs of my ladder, while 3 and 4 designate the rear legs thereof. The front legs may either be parallel to each other or may diverge as 45 they approach the floor. The rear legs are preferably so constructed as to always be wider apart at the bottom than the top. The legs are provided with the joints 5, located preferably, near the middle thereof. The 50 front legs, at their upper ends, are bent inwardly at an angle somewhat greater than a right angle, forming the sections 6, (shown

in Fig. 2,) to the inner sides of which are riveted the angles 7, to which is secured the platform 8. The rear legs, at their upper ends, 55 are pivotally connected to the bent section 6 of the front legs and near the center of said sections. At equal intervals apart throughout the length of each of the front legs I secure by rivets the angles 9, upon which are mounted and suitably secured the steps 10. The rear legs are provided, in the upper portion thereof, with the ears 11, designed to receive pivots 12, which support the movable shelf 13 in its proper position, said shelf being supported by the narrow strips 14, the inner sections of which curve slightly downward. Said strips, near the center thereof, receive the inner ends of the pivots 12, while the ends of the bent sections bear up against 70 the under side of the upper step. Said ends are connected by the rod 15, which is riveted or otherwise rigidly secured thereto. (Shown in dotted lines in Fig. 1.)

The steps 10 being secured to the front legs, 75 as shown, serve to brace them together, while the rear legs are provided, both in the top and bottom sections, with the braces 16 and 17, respectively. Said braces are secured at their outer or extreme ends by rivets and at their 80 inner or mean ends by stay bolts or bars 18 and at their centers are riveted to each other. Said braces are made of lattice-iron, their ends being twisted and bent so as to lie against the legs parallel thereto. The inner or mean ends 85 of the two pairs of braces 16 and 17 are provided with holes which register with corresponding holes in the legs 3 and 4 of the ladder. The bolts 17, at either end thereof, are passed through these registering holes, and on 90 the outer ends of said bolts are located the nuts 19, while the nut 20 is screwed home against the inner side of the twisted section of the braces, thus rigidly uniting the ends of the braces to the legs of the ladder. The pair of 95 braces 17 is further reinforced, at the lower end thereof, by the transverse bar 17^a, the ends of which are bent so as to lie against the ends of said braces, where they are secured to the braces and the legs by rivets. The upper pair 100 of braces 16 needs no such reinforcement, as the platform 8 supplies this need.

When in use, the front and rear legs are held in proper relative position to each other

by the safety spring-hooks 21. Said hooks are pivotally secured to the front legs by staples 22 or other preferred means and are received at the hooked end thereof by staples or eyes 23, secured to the rear legs.

When it is desired to fold the ladder, the hooks are removed from the eyes or staples 23 and are received by the eyes 24, located on the outer sides of the front legs, in the upper section thereof.

One of the joints 5 is illustrated in detail in Fig. 3 and is formed as follows: The upper section of the leg, near the lower end thereof, is bent inwardly, forming the section 25, then outwardly, forming the section 26, which is parallel to the main section of the leg. This section 26, at the lower end thereof, terminates in an upward and outward bend, forming the hook 27, the plane of which is substantially at right angles to the longitudinal reach of the leg. Near the upper end of the section 26, on the outer side thereof, the lower section of the leg is pivotally connected thereto. The washer 28 is received by the pivot between the two sections of the leg, the object of which is to lessen the friction in folding and unfolding. The section 26 is further provided with the aperture 29, which when in operative position registers with a corresponding aperture in the lower section of the leg, said apertures being designed to receive the pin 33, which locks the joint, so to speak. Said pin is carried by the strap-spring 30, which is pivoted to the upper section of the leg just above the bend 25. For convenience in manipulating this spring is provided at its lower end with the outwardly-bent section 31, which terminates in the curve 32. The sections 26 are provided with the ears 34, having the apertures 35, adapted to receive the journals 36, which unite the upper and lower sections of each leg. The lower sections of the legs, at their upper ends, have a short inner bend which is provided with an aperture 34 which registers with the aperture 35, receiving the other end of the journal 36. The hooks 27 prevent the lower sections of the legs from moving outwardly too far, even though the joint should not be locked by the pin 33, carried by the spring 30.

The legs of my ladder are provided, at the lower ends thereof, with the malleable-iron feet 37, to which said legs are pivoted, as shown. Said feet may be rectangular or oblong in shape and are each provided with the upwardly-extending ears 37^a and the central cut-away portion 37^b, adapted to receive the lower ends of the legs between said ears where said legs are secured by pivots 37^c, which are journaled in said ears. The feet are further provided on their bottoms with the small points 37^d, designed to engage with the floor or carpet to prevent the ladder from sliding when in use, even though the safety spring-hooks 21 should by accident become broken or disengaged. It is thought that these feet will form a desirable addition to any step-

ladder. When it is found necessary to have as many of these points as possible on the bottom of the feet in order that they may be made the smaller, the cut-away portion 37^b need not extend entirely through the feet.

When it is desired to partially fold my ladder, as illustrated in Fig. 2, the safety spring-hooks 21 are unhooked from the eyes 23, the pin 31, carried by the strap-spring 30, being withdrawn, and the spring is moved outwardly, as shown, to prevent them from coming in contact with the floor when the ladder is used in this partially-folded condition. The lower ends of the rear legs are then bent inwardly and upwardly. Next the lower end of the front legs are likewise bent inwardly and upwardly until they occupy the position illustrated in Fig. 2. The spring-hooks 21 are again placed in operative position, as shown. The ladder can then be used where only a low ladder is required. When in this position, the lower ends of the sections 26 form the feet of the ladder. The shelf, being in its operative position, may be used to accommodate buckets, boxes, or anything of the kind that may be required.

When it is desired to fold the ladder into the smallest possible compass for shipping, &c., the curved sections 14 of the shelf-supporting straps are moved downwardly till their lower ends lie against the upper braces 16. This of course causes the shelf to rise and lie against the outer edges of the rear legs, immediately under the platform. Then the lower sections of the rear legs are folded inwardly and upwardly till the braces 17 lie against the straps 14. Next the lower sections of the front legs 5 are likewise folded inwardly and upwardly till the rear edges of their steps lie against the inner edges of the upper sections of said legs. The safety spring-hooks 21 are hooked into the eyes 24, and the lower ends of the ladder thus folded are drawn together till the braces 17 lie against the infolded steps of the front legs. This brings the entire ladder into a very small compass.

In the construction of my ladder I prefer to use iron chiefly, making only the steps, platform, and shelf of wood, while the strap-springs 30 may be made of brass, though it will be understood that I do not limit myself in the matter of material.

Having thus fully described and illustrated my invention, I yet do not wish to limit myself to the exact showing made, but desire protection in all that comes clearly within the spirit and scope of my invention.

Having thus fully described my invention, what I claim as new, and desire to secure by Letters Patent, is—

1. A ladder having two leg-sections pivoted together, fingers or extensions of the upper section lying against the forward edge of the lower section below said pivot-point, and each having perforations, there being registering perforations formed in the lower section, and

a spring-controlled pin taking into each of them, whereby the leg-sections will be locked against movement, substantially as specified and for the purpose set forth.

5 2. As an improvement in step-ladders, an upper section and a lower section hinged together, the upper section provided in its lower end with a curved lip, a rivet or journal secured to an extension of the upper section and designed to pivotally unite the lower section thereto, an antifriction-washer surrounding said journal and disposed between said sections and means consisting of a spring-controlled pin for locking the leg-sections in 15 an extended position, as and for the purpose set forth.

3. As an improvement in ladders, a hinge for joining the upper and lower leg sections

upper section and designed to be received by 20 an aperture in the lower section, said sections lying substantially parallel with each other, an antifriction-washer interposed between them, there being perforations formed in the upper end of the lower sections, and a 25 spring-controlled pin carried by the upper section and designed to fit in said perforation formed in the lower section, said pin or spring having a lateral projection for manual control thereof, as specified and for the purpose set forth. 30

In testimony whereof I affix my signature in presence of two witnesses.

CHARLES HENRY LIKEWISE.
